JOHN S. HARLEY, OF MINNEAPOLIS, MINNESOTA, ASSIGNOR, BY MESNE ASSIGNMENTS,
TO UNIVERSAL AUTOMATIC ELECTRIC SIGNALING COMPANY, OF LA CROSSE, WIS-
CONSIN, A CORPORATION OF WISCONSIN.

ELECTRIC SWITCHING MECHANISM.

1,031,849.

Specification of Letters Patent.

Patented July 9, 1912.

Application filed May 22, 1911. Serial No. 628,874.

To all whom it may concern:

Be it known that I, JOHN S. HARLEY, a citizen of the United States, residing at Minneapolis, in the county of Hennepin and 5 State of Minnesota, have invented certain new and useful Improvements in Electric Switching Mechanism, of which the following is a specification.

My invention relates to a new form of 10 switching device for automatically closing certain circuits and opening others with absolute precision and certainty.

In certain fire alarm systems, such for example as that described in my application, Serial Number 628,873, dated May 22, 15 1911, for fire alarm system, a plurality of circuits are used one of which may be closed at all times and the others open at all times, breakage of the closed circuit being designed 20 to operate means to close the open circuit and thereby set in operation signaling and alarm devices. My switching device provides the means whereby through the operation of one circuit the said switching device 25 may be caused to operate one or more additional circuits, either by closing some of them and opening others or otherwise, as desired.

In the drawings illustrating the application of my invention in one form,—Figure 30 1 is a side elevation and Fig. 2 a plan of my switching mechanism in position to be operated. Figs. 3 and 4 are similar views of my mechanism after the same has been operated.

35 A switchboard 5 has secured thereto a pair of ears 6 and 7 between which is pivoted a bar 8 of rectangular cross section, as shown in section in Figs. 1 and 3, said bar being provided with trunnions 9 forming 40 bearings for the same in the ears 6 and 7. Rigidly secured to the bar 8 midway of the ends thereof is an arm 10 having an outwardly extended weighted end 11. The arm 10 is provided with a hook 12 extending in 45 wardly from said arm when the same is in raised position and adapted to coöperate in a vertical plane when in such position with a hook 13 pivoted at 14 to a member 15 secured to the switchboard 5, the coaction of 50 the hooks 12 and 13 holding arm 10 in raised position so that when hook 13 is lifted arm 10, under the influence of gravity acting upon the weighted end 11, is free to fall. As shown, the hook 13 is connected to

55 armature 16 of relay 17, in the normally open circuit of which connecting wires 18 and 19 are a part. When said open circuit is closed it operates to lift armature 16 and attached hook 13 thereby releasing member 10 and permitting it to fall. In this connection it may be stated, however, that a reversal of this condition whereby relay 17 is 60 in a closed circuit, the opening of which will permit armature 16 to fall and thereby release member 10, is contemplated by me and falls within the scope of my invention. 65 Wires 20, 21 and 22, 23 are connected with contacts 24, 25 and 26, 27, respectively, said wires being a part of a main signaling circuit. The double break in the said signaling 70 circuit thus provided is adapted to be closed by means of knife switches 28, 29 rigidly secured to the cross bar 8, such knife switches being wedge-shaped in cross section, as clearly shown in Fig. 2. The upper ends of 75 contacts 24, 25, 26, 27 are formed of spring metal and bifurcated. When member 10 is released and permitted to fall the knife-like switch members 28, 29 are forced between the bifurcated ends of said contacts thereby 80 having perfect circuit-closing engagement with said contacts.

In the operation of the system described in the above enumerated application or in other systems where it is desirable to actuate signaling means located at the fire station or some other central station, an independent circuit is employed which may be a closed circuit, and my switching device is provided with means for opening said 85 closed circuit at the same time that the signaling circuit within the building is closed. In the form shown, contacts 30 and 31 are 90 connected with the wires 32 and 33 of such fire station circuit. Pivotaly attached to 95 contact 30 at 34, in such manner as to have a stiff movement thereon so that the same will remain wherever set, is a switch member 35 which, when the member 10 is in raised position, is held 100 in circuit closing engagement with contact 31 by means of a projection 36 on said arm 10. The arm 10 is provided with a hook 37 which extends vertically upwardly 105 when the member 10 is in its raised position, said hook 37 in such position engaging beneath the extended end 38 of the switch 35. When, therefore, the member 10 falls the

- hook 37 will operate to lift the switch 35, as shown in Fig. 3, thus breaking the fire station circuit. On account of the member 35 being hinged to contact 30 in such manner as to have frictionally retarded or stiff movement, such switch member 35 will remain in its disconnecting position until member 10 is raised and switch 35 pushed back by projection 36.
- 16 It is sometimes desirable, after circuit including relay 17 has been closed and member 10 released, to re-open said circuit. This may be accomplished automatically by providing in connection with the wire 19 and an intermediate wire 39 a spring contact 40 which may be operated by a nose 41 formed on the end of the member 10 below its point of connection to bar 8. When member 10 falls the action of nose 41 upon spring contact 40 will be to break the relay circuit, as shown in Fig. 3.
- 15 The operation of my switching device has been very fully given in connection with the detailed description thereof. It is simple and certain of action and may be readily adapted to close or open any desired number of circuits simultaneously, or open some of said circuits and close others, as shown.
- 20 I claim:
- 36 1. In an electric system, a plurality of electric circuits, a switchboard where said circuits center provided with contacts breaking said circuits, a switch pivoted to a contact of one of said circuits adapted to close the same, a weighted pivoted arm, means to hold said arm in raised position, means operated by one of said circuits to release said arm, a projection on said arm adapted to engage the pivoted switch and force the same into position to close the circuit when said arm is raised, and a hook-like member extending beneath and engaging the free end of said switch and adapted to lift the same to open the circuit at the moment when the arm starts to descend.

2. In an electric system comprising a plurality of electric circuits, one of which is normally held open, a pivoted bar, knife switches rigidly secured by non-conducting means to said bar, a weighted arm secured at one end to said bar, means for holding said arm raised, a relay in another circuit, energizing of said relay operating to release the arm and permit gravity to operate the same and cause the knife switches to close the open circuit, means for breaking the relay circuit, and means on the arm whereby the falling thereof will operate said relay circuit-breaking means.

3. In an electric system comprising a plurality of electric circuits and a relay in one of said circuits, a circuit closing and opening device comprising a pivoted bar, a plurality of knife switches rigid on the bar adapted to close a circuit normally open, an independent switch pivoted to a contact of another circuit normally closed and adapted to open said circuit, a weighted arm rigidly secured to the bar near one end of said arm, means for holding said arm in raised position, part of said means being connected with the armature of the relay which is operative to release said arm, a projection on the arm engaging said independent switch and holding it in circuit-closing position when the arm is raised, and a second projection extending upwardly from the pivoted end of the arm beneath the free end of the independent switch when the arm is in raised position, falling of said arm operating to cause said second projection to lift the independent switch and open the closed circuit and the knife switches to close the open circuit.

In testimony whereof I affix my signature in presence of two witnesses.

JOHN S. HARLEY.
